United States Patent Office

Des. 216,756
Patented Mar. 3, 1970

216,756

MANICURE TRAY

Donald E. Everburg, Southbridge, Mass., assignor to
American Optical Corporation, Southbridge, Mass., a
corporation of Delaware

Filed Dec. 19, 1968, Ser. No. 15,058

Term of patent 7 years

Int. Cl. D6—01
U.S. Cl. D86—10

FIG. 1 is a perspective view of a manicure tray showing my new design;

FIG. 2 is an end view thereof, the opposite end being identical thereto;

FIG. 3 is a side elevational view, the opposite side being identical thereto;

FIG. 4 is a top plan view thereof.

I claim:

The ornamental design for a manicure tray, substantially as shown and described.
